UNITED STATES PATENT OFFICE.

OSCAR HOCHBERG, OF ST. LOUIS, MISSOURI, ASSIGNOR TO AMERICAN CAR AND FOUNDRY COMPANY, OF ST. LOUIS, MISSOURI, A CORPORATION OF NEW JERSEY.

DRAFT-ARM.

1,208,963.

Specification of Letters Patent. Patented Dec. 19, 1916.

Application filed August 2, 1916. Serial No. 112,722.

To all whom it may concern:

Be it known that I, OSCAR HOCHBERG, residing at St. Louis, Missouri, and being a citizen of the United States, have invented 5 certain new and useful Improvements in Draft-Arms, of which the following is a full, clear, and exact description, such as will enable others skilled in the art to which it appertains to make and use the same, reference being had to the accompanying drawings, which illustrate the preferred form of the invention, though it is to be understood that the invention is not limited to the exact 10 details of construction shown and described, as it is obvious that various modifications thereof within the scope of the claims will occur to persons skilled in the art.

In said drawings: Figure 1 is a plan view 20 of a portion of an underframe of a car equipped with a reinforcing draft arm, the upper portion of the figure illustrating a horizontal section taken substantially on the line 1-1 of Fig. 2 through the draft plate 25 sill and draft lug; Fig. 2 is a longitudinal vertical sectional view of the end portion of the underframe showing the draft arm applied; Fig. 3 is a vertical sectional view taken on the line 3-3 of Fig. 2; Fig. 4 is a similar view taken on the line 4-4 of Fig. 2; and Fig. 5 is an enlarged view of a portion of the section taken on line 1-1 of Fig. 2, showing the draft lug fitted within the depressed socket of the draft plate.

35 While most of the rolling stock of railways of the present day is modern, there still remains in service a considerable number of old all wood cars, the condition of which does not warrant discarding them, but which do not possess the proper inherent strength to be included in trains made up of the now more heavy cars. Using the old wood cars is a more or less dangerous practice, unless their underframes 40 are reinforced to withstand the heavy 45 stresses of modern train operation.

The present invention relates to a draft arm which may be applied to the wooden center sills of old cars in such manner that 50 they will reinforce the same and provide a strong metallic structure capable of meeting all the requirements they may be subjected to.

55 It is a purpose to include in the draft arm herein disclosed, a reinforcing draft plate

in which sockets are formed by a novel method of slitting and pressing such plate, whereby there are portions bulged inwardly away from the body of the draft plate to provide abutments for the lugs or projections and bearing surfaces of the outer faces of the draft lugs. In this way the draft lugs over the greater portion of the distance between the follower stops are provided with considerable bearing area in addition 60 to that furnished by that portion of the plate lying between the draft lug projections and the draft sill.

Other features of merit will become apparent hereinafter and are to be considered 70 parts of the invention.

Referring to the drawings, an end portion of an underframe has been shown and it is to be understood that the opposite end of the underframe is of similar construction, 75 and therefore it is unnecessary to describe more than one of the underframe ends.

Referring specifically to the parts, 1 indicates reinforcing plates disposed on opposite sides of the center line of the underframe, each of which plates comprises an upper portion and a lower portion, the upper portion having an inwardly directed flange 2 at its outer end securely bolted or otherwise fastened to the end sill 3 of the underframe. Said upper portion extends from end sill 3 rearwardly to beyond the bolster 4, passing over the same. The lower portion passes partially underneath end sill 3, said lower portion extending rearwardly. The 80 lower portion of each plate 1 extends substantially to the forward edge of bolster 4. As seen in Figs. 3 and 4, the upper portion of each reinforcing plate 1 lies against the inner face of the wooden center sill C and is 85 secured thereto by horizontally disposed bolts 6 arranged longitudinally of center sills C, as disclosed in Fig. 2. Toward the lower edge of center sills C, plates 1 are inclined outwardly and depend a material distance below the inclinations and also the bottoms of the center sills, the center sills being cut away to accommodate the offsetting of plates 1. The lower portion of plates 1 are therefore transversely spaced 90 a suitable distance to accommodate the draft gear, not shown, used in the car before the substitution of the reinforcing draft arm. Draft lugs 7, previously used in the 95 all-wooden underframe construction, are 100

105 110

retained in the present draft arm arrangement, appropriate provision being made for the lugs or projections 8 which, in the original car, were embedded in recesses in the 5 composite wood center and draft sills, as hereinafter more fully set forth.

Associated with reinforcing plates 1 are draft sills 9, here illustrated as having the form of commercially rolled channels. 10 Draft sills 9 have their upper flanges arranged to abut the bottoms of the wood center sills C and are secured thereto by bolts 10 passing through the upper draft sill flanges, center sills C and the floor 11, 15 the heads of bolts 10 being countersunk in said floor. The inner faces of draft sills 9 lie against the outer faces of reinforcing plates 1, except where portions of the latter are bulged inwardly therefrom, and the 20 lower flanges of draft sills 9 form stiffening members for the bottoms of the reinforcing draft arms. Draft sill channels 9 extend forwardly under end sill 3, and beyond the same, and have a striking plate 25 casting 5 secured to their outer ends. In progressing rearwardly, draft sills 9 extend to the rear of the lower portions of plates 1, which lower portions terminate at the forward side of the bolster. The upper rear 30 portions of draft sills 9 and the lower portions of plates 1, which they reinforce, are connected by upper tie plates 12 provided with down-turned flanges 12^a, rivets 13 passing through these flanges, the lower portions 35 of plates 1, and the webs of the draft sills 9. The horizontal or body portion of tie plates 12 abut the upper forward flange 14 of the bolster 4. The upper portions of plates 1 are also reinforced by channel or 40 other suitable members 15 secured to said upper portions at a point forwardly of the bolster and extending rearwardly thereof, preferably to the rear ends of the upper portions of plates 1. Another tie plate, which 45 may be in the form of an angle 16, is secured to the bottom flanges 17 of the transversely spaced channels 15, said angle 16 abutting the upper rear bolster flange 18. With this arrangement, buffing and pulling 50 stresses will be directly transmitted to the bolster and in such manner as to relieve the securing bolts 19 from the effect of such stresses. On account of the described combination of the parts of the draft arm, said 55 arm as a whole is more rigidly positioned by reason of the interlocking between the bolster 4 and the tie plates 12 and 16.

The lower portions of the plates 1 are given novel treatment to adapt them to co-operate with the draft lugs 7. At suitable 60 points, embossments 22 are made in said lower portions of plates 1 which embossments are spaced inwardly from the webs of draft sills 9. On opposite sides of the 65 vertical median line of each embossment,

incisions are made to form slits 20. The metal of each embossment between the companion slits 20 is rebent at 21 outwardly to contact with the inner faces of the vertical webs of the draft sills 9. The vertical 70 extent of the rebent portions 21 is, preferably, nearly equal to the height of the embossments 22, as best shown in Figs. 2 and 3. Draft lugs 7 are provided with bearing bosses 23 which lie against the embossments 72 22 of plates 1, and centrally of each draft lug bearing boss 23 is a lug or projection adapted to fit into the space formed by depressing the rebent portions 21 of plates 1. Projections 8, as shown in Fig. 4, are 80 substantially of the same height as the sockets formed by rebending portions 21, and rivets 24 pass through the projections 8, the metal of the rebent portions 21 that is centrally located of the embossments 22, 85 and the webs of draft sills 9. By reason of the inward extension of bosses 22 of plates 1, the ends of draft lugs 7 are spaced away from the inner faces of said plates 1 and fillers 25 are interposed between said plates 90 and the ends of draft lugs 7, rivets 26 passing through the draft lugs 7, fillers 25, plates 1 and the webs of draft sills 9. The lower portions of plates 1 are secured to the draft sills 9 by rivets 26 and 27, which 95 rivets are disposed between and on opposite sides of the embossments 22 of said reinforcing draft plates 1.

From the foregoing, it is evident that 100 buffing and pulling stresses will be transferred from draft lugs 7, through the lugs or projections 8, to the edges of the metal of the embossment which are formed by the incisions producing slits 20, thence through plates 1 to the tie plates 12 and 16 and to the bolster, thus relieving the wooden center sills C of a great portion of 105 disrupting forces. Shocks sustained by the striking casting will be transmitted from the same to draft sills 9, to plates 1 and 110 to tie plates 12, which transfer the same to the bolster 4. It will be seen that draft lugs 7 are provided with considerable bearing area between the follower stops 28 by 115 embossments 22, in addition to the bearing secured by the contacting of the outer faces of projections 8 against the rebent portions 21 of embossments 22, which rebent portions lie against the webs of draft sills 9.

What I claim is:

1. In combination in a car underframe, wooden center sills, metallic plates paralleling and secured to said sills and draft lugs, provided with projections, said plates having embossments containing companion incisions and being depressed between the latter to form sockets into which said draft lug projections extend.

2. In combination in a car underframe, wooden center sills, metallic plates parallel-

- ing and secured to said sills, draft sills connected to said center sills and plates and draft lugs provided with projections, said plates normally lying against the draft sills and having bearing bosses for said draft lugs spaced from the draft sills and depressed at certain localities to engage said draft sills and to form sockets for said draft lug projections. —
- 10 3. In combination in a car underframe, wooden center sills, opposingly spaced metallic plates paralleling said sills, secured to the inner faces thereof and depending below the bottoms of said sills, the depending portions of said plates being more widely spaced than the sill-secured portions thereof, stiffened draft sills reinforcing said plates, and draft lugs secured to the depending plate portions, said lugs and plates having opposing and interlocking bearing bosses inwardly spaced from the draft sills.
- 15 4. In combination in a car underframe, a draft sill, a metallic plate secured thereto and provided with an embossment spaced therefrom, there being spaced slits in said embossment, the metal between adjacent slits being pressed out of alinement with the body portion of said embossment, and a draft lug having a projection adapted to bear against the slit-formed edges of the embossment.
- 20 5. In combination in a car underframe, a draft sill, a metallic plate secured thereto and provided with an embossment spaced therefrom, said embossment containing parallel slits, the metal between which is deflected to lie against said sill, a draft lug having a projection extending into the space between the embossment edges formed by said slits and engaging said deflected metal and a fastening device connecting said draft lug projection, deflected metal portion and draft sill.
- 25 6. In combination in a car underframe, draft sills, metallic plates positioned against the inner faces of said sills, each plate having embossments spaced from its associated draft sill, said embossments containing parallel slits, the metal between which is deflected toward the adjacent draft sill to form sockets, draft lugs having projections entering said sockets, the end portions of said draft lugs being spaced from said plates, fillers between draft lug end portions and plates, and means securing said draft sills, metallic plates, fillers and draft lugs together.
- 30 7. In combination in a car underframe, an end sill, a bolster, wooden center sills, metallic plates paralleling said center sills, secured thereto and to said end sill and extending beyond the rear of said bolster and below said center sills, draft sills reinforcing the plate portions below said center sills, the lower body portions of said plates lying
- against said draft sills and having inwardly bulged embossments each provided with incisions, the metal between which is rebent into alinement with said body portions, draft lugs having projections fitting into the spaces formed by the rebent embossment portions and the incision edges of the metal of said embossments, and means securing said draft lugs, plates and draft sills together.
- 35 8. In combination in a car underframe, a bolster, wooden center sills, opposingly spaced metallic plates having upper portions secured to said center sills and extending rearwardly of the bolster and lower portions depending below said sills, means for transmitting stresses in said plates to opposite sides of said bolster, said plates having body portions lying against said draft sills and inwardly bulged embossments each provided with slits and portions between said slits rebent to engage the draft sills, and suitably retained draft lugs having projections extending between the edges of the embossments formed by the slits and contacting with said rebent embossment portions. —
- 40 9. In combination in a car underframe, a bolster, wooden center sills, metallic plates extending with said sills, secured thereto and depending therebelow, draft sills and draft lugs secured to the depending portions of said plates, a striking casting connected to said draft sills, said plates having embossments provided with slits, the metal between said slits being rebent to form sockets, said draft lugs having projections adapted to be seated in said sockets and to engage said rebent embossment metal and the edges of the embossment formed by said slits, and a member abutting said bolster and rigidly connected to said draft sills.
- 45 10. As an article of manufacture, a draft appliance constructed to be used in cars having center sills, said article comprising metallic plates adapted to parallel and be secured to the sills and draft lugs provided with projections, said plates having embossments containing companion incisions and being depressed between the latter to form sockets into which said draft lug projections extend.
- 50 11. As an article of manufacture, a draft appliance constructed to be used in cars having center and draft sills, said article comprising metallic plates adapted to parallel and be secured to the center and draft sills and draft lugs provided with projections, said plates having body portions adapted to lie against the draft sills and also having bearing bosses for said draft lugs adapted to be spaced from the draft sills and depressed at certain locations to engage the draft sills and to form sockets for said draft lug projections.
- 55 12. As an article of manufacture, a draft appliance constructed for use in cars having

center sills, said article comprising opposingly spaced metallic plates adapted to parallel and be secured to sides of the center sills and to depend below said sills, the depending portions of said plates being spaced to a different degree than the sill-secured portions thereof, stiffened draft sills secured to and reinforcing said plates, and draft lugs also secured to the depending plate portions, 10 said lugs and plates having opposing and interlocking bearing bosses inwardly spaced from the draft sills.

13. As an article of manufacture, a draft arm constructed to be used in a car having 15 a center sill, said article comprising a draft sill adapted to be attached to the center sill, a metallic plate secured to the draft sill and provided with an embossment spaced therefrom, there being spaced slits in said 20 embossment, the metal between adjacent slits being pressed out of alinement with the body portion of said embossment, and a draft lug having a projection adapted to bear against the slit-formed edges of the 25 embossment.

14. As an article of manufacture, a draft appliance constructed for use in a car having spaced central sills, said article comprising 30 draft sills adapted to be secured to the central sills, metallic plates secured to the draft sills and each provided with embossments spaced from its associated draft sill, each embossment containing parallel slits, the metal

between which is deflected to lie against the adjacent draft sill, draft lugs provided with 35 projections extending into the spaces between the embossment edges formed by said slits and engaging said deflected metal, and fastening devices connecting said draft lug projections, deflected metal portions and 40 draft sills.

15. As an article of manufacture, a draft appliance constructed for use in a car having center sills, said article comprising draft sills adapted to be secured to said center 45 sills, metallic plates adapted to be positioned against the inner faces of said center sills, and to be secured thereto, each plate having embossments spaced from its associated draft sill, said embossments containing parallel slits, the metal between which is deflected toward the adjacent draft sill to form sockets, draft lugs having projections entering said sockets, the end portions of said draft lugs being spaced from said 50 plates, fillers between the draft lug end portions and plates, and means securing said draft sills, metallic plates, fillers and draft lugs together.

In witness whereof I have hereunto set 55 my hand in the presence of two witnesses.

OSCAR HOCHBERG.

Witnesses:

BLASDEL SHAPLEIGH,
JOHN M. ROHLFING.
